UNITED STATES PATENT OFFICE.

NOËL DEERR, OF BROOKLYN, NEW YORK.

EVAPORATOR.

1,287,650.

Specification of Letters Patent. Patented Dec. 17, 1918.

Application filed August 16, 1917. Serial No. 186,573.

To all whom it may concern:

Be it known that I, NOËL DEERR, a British subject, residing in the United States at 28 Fort Greene Place, in Brooklyn, in the county of Kings and State of New York, have invented a new and useful Evaporator, of which the following is a specification.

My invention relates to apparatus for economically concentrating solutions by the evaporation or distillation of the solvent and particularly refers to the evaporation of solutions, such as beet and sugar cane juices, tan bark extracts, caustic soda solutions and the like. The objects of my invention are first, to separate the incondensable gases from the steam or vapors used to effect evaporation in a more natural and efficient manner than has been accomplished in the past by other evaporators of record; second, to drain the condensate from the calandria of the evaporator in a simpler and more efficient manner than has been accomplished in the past; third, to obtain a greater heating surface per unit of space, without adding any detrimental hydrostatic pressure to the boiling liquids, than can be obtained by the usual cylindrical bodies of other evaporators using vertical tubes; fourth, to provide a uniform distribution of the liquid entering an effect over the heating surface and a uniformly distributed withdrawal of the liquid leaving an effect; fifth, to design a type of evaporator which embodies the simplest type of construction; necessitates the making of the least number of patterns, many of which may also be used for an apparatus of any size; minimizes the amount of machine work required; and makes an apparatus less expensive to construct than known evaporators and at the same time more efficient in operation; sixth, to provide a "downtake" or passage for the circulation of the boiling mass in such a suitable location and of such a shape that a more rapid circulation can be obtained than has been possible heretofore.

The invention consists in the novel parts, constructions, arrangements, combinations and improvements herein shown and described.

The accompanying drawings herein referred to and constituting a part hereof, illustrate one embodiment of the invention,

and together with the description serve to explain the principles thereof.

Of the drawings:

Figure 1 is a front elevation of a multiple effect evaporator; in this particular instance a triple effect evaporator;

Fig. 2 is a combination end elevation of one cell and a sectional elevation through said cell taken on the line 2—2, Figs. 3 and 4; Fig. 3 is a sectional plan view on the line 3—3 Figs. 1 and 2;

Fig. 4 is a sectional plan view taken at 4—4, Figs. 1 and 2.

Fig. 5 is a section through the calandria of a cell showing the means adopted to obtain the uniform distribution of liquid entering an effect and uniform withdrawal of the liquid leaving an effect as applied to apparatus of large size and larger than that indicated in Figs. 1, 2, 3 and 4.

Similar letters refer to similar parts throughout the several views.

In the exemplified embodiment of the accompanying drawings, A, B and C are cells of a multiple effect evaporator in which A is the first cell and receives steam into its calandria through the openings d. B is the second cell, and the liquid therein is caused to boil solely by the heat of the vapors arising from the boiling liquid in the 1st cell, A.

Similarly the vapors arising from cell B flow through pipe e to the calandria f and cause the liquid of cell C to boil in turn. A high vacuum is maintained in the vapor space of cell C; a vacuum of less degree in the vapor space of cell B and calandria of cell C; a slight degree of vacuum only is required in the vapor space of cell A and the calandria of cell B; steam pressure of about 1 pound per square inch or more is usually supplied to the calandria of cell A.

It is due to the difference in the vacuum that one cell has over the other that enables the vapors of one cell to boil the liquid in the next cell in series, for it is a natural law that the boiling point of a liquid decreases as the vacuum under which ebullition occurs increases.

The foregoing explanation of the operation of a multiple effect evaporator was thought to be desirable for it will aid in better understanding the nature of my invention. No claim for originality however

in the above description of the process of multiple effect evaporation is contemplated.

A comparison between the known types of evaporators and my own evaporator herein disclosed, will serve to accentuate the merits of my invention.

In the so called "standard vertical submerged tube evaporator", the steam belt consists of a vertical cylindrical shell in which are arranged two horizontal tube sheets, one upper and one lower.

The sheets are perforated and into each hole an end of a vertical tube is rolled.

These sheets and tubes together form a part of the apparatus known as a calandria. Steam is admitted to the space between the tubes. The material to be evaporated is contained within the tubes and above and below the tube sheets.

In what is known as the "horizontal submerged tube evaporator", the tube sheets are vertical and the tubes run horizontally. In this type, the steam is contained within the tubes and the material to be evaporated between the tube sheets and on the outside of the tubes. Both designs have their advantages: in the vertical tube apparatus, the tubes can be mechanically cleaned in position, while in the horizontal type they have to be removed from the apparatus; in the vertical apparatus a more effective circulation can be given to the material undergoing evaporation, than is the case in the horizontal tube apparatus. With respect to the elimination of the undesirable incondensable gases and the condensed water, my invention equals or surpasses the horizontal submerged tube apparatus.

As before stated neither the vertical submerged tube apparatus nor the horizontal submerged tube apparatus combine these qualities.

Referring more in detail to the embodiment of the accompanying drawings, the cell or effect is preferably substantially rectangular considered in horizontal cross-section, and is provided in its bottom part with a calandria and a circulatory system for the juice or other solution to be concentrated.

In the present preferred embodiment, the steam or other heating vapor has a straight-away passage way or conduit from its inlet to the outlets for the condensate and the non-condensable vapors so constructed and arranged that no part of the rapidly rushing body of steam or other heating vapor interferes with or backs up against any other part thereof, so as to negative or interfere with a free and uniform distribution and travel of the heating vapor; but on the contrary such a free and uniform flow of the heating vapors is secured, that uniform and efficient heating and circulation of the liquid under concentration is always maintained.

In connection with the means for effecting

such uniform heating and circulation through and about the calandria of the liquid under concentration, simple and efficient means are provided for removing the condensate and the incondensable gases, all said means co-operating together and conducing to the general desirable results and advantages set forth.

In Fig. 3 the calandria is divided into two straight-away steam spaces, with a down-take *n* extending along substantially the entire length of the calandria. Through each steam space extend the liquid heating and conducting pipes *m*, the down-take *n* receiving the flow from the pipes *m* on both sides thereof. In Fig. 5 the calandria is divided into three steam spaces or straight-away chambers, with two down-takes *n*, one between each two steam spaces or chambers.

Each steam space or chamber has an intake or supply pipe *d* for the heating vapor located at one end thereof.

In the embodied form, the calandria comprises a top plate *l* and a bottom *l'*, the latter being preferably flat and inclined downwardly from the end where the heating vapor enters to the end where are located the outlets for the condensate and for the incondensable vapors, both the top and bottom plates being preferably flat and attached to the side walls of the cell. There is thus provided a unidirectional conduit for the heating vapor, which is preferably rectangular in cross-section.

The vertically arranged tubes *m* are mounted in the top and bottom plates *l* and *l'* and open into the cell both at their tops and bottoms and constitute the chief heating means and the upward channels for the circulating fluid undergoing concentration. The cluster of tubes *m* is preferably arranged substantially along and throughout the extent of the conduit, spaced apart sufficiently to permit adequate passage space for the current of heating vapor. Passageways *o* are left in the group of tubes *m* so located and disposed with respect to the inlet and path of travel of the heating vapor as to cause equal distribution of the heating vapors throughout the tubes *m* and the entire heating area.

Suitable downwardly directing means for the circulating liquid undergoing concentration is provided in such relation to the tubes *m* as to insure a uniform, unimpeded and non-conflicting flow and circulation from the tops of the tubes back to the bottom thereof. As embodied, a downtake passage *n* extends substantially the entire length of the tube cluster, and is disposed longitudinally of the direction of the heating vapor flow, the vertically and longitudinally disposed walls *j* of this intake connecting with the top plate *l* and bottom plate *l'*. The downtake thus communicates with the body

- of the cell both above and below along the entire length of the tubes and conduit, and the side wall thereof constitutes a side for the conduit or chamber along and within 5 which the heating vapor rushes through the tubes m . The opposite wall of the conduit or chamber is formed by the side wall k of the cell (as shown in Fig. 1) or by another downtake (as shown in Fig. 5).
- 10 Referring now more particularly to the construction and arrangement of the means for supplying and directing the heating vapor, and for withdrawing the condensate and the incondensable gases, the inlet into 15 the calandria for the heating vapor is indicated by d , and it is located at one end of the conduit or chamber just described. At the opposite end of the conduit or chamber, which is likewise remote from the vapor 20 inlet d are the exits or outlets for the incondensable gases, and in accordance with one feature of the invention there is provided a relatively large number of spaced apart exit or exhausting orifices for the gases, prefer- 25 ably located relatively closely together and disposed or located both vertically and horizontally throughout the entire end of the heating vapor chamber which is opposite the inlet d .
- 30 As embodied, there are a plurality of spaced apart, vertically disposed pipes y arranged entirely across said opposite end of the chamber. These pipes y are provided at intervals throughout their length with 35 gas admitting orifices z . The pipes y at their upper ends empty into a header g , this header in turn emptying through a pipe g' into the pipe or conduit e which conducts the vapors produced from the boiling liquid 40 from the cell into the next succeeding cell or effect. This pipe g' may be supplied with a regulating valve g^2 .
- Means are provided by the invention for 45 conducting away the condensate from the heating vapor chamber, and as embodied, a plurality of draining pipes h' open downwardly from the floor or bottom sheet l' of the calandria, the pipes being spaced apart across the end of the heating vapor chamber, 50 as will be seen from Figs. 1 and 2. These draining pipes empty into a manifold or header h arranged therebeneath and draining in turn into a pipe h^2 . The bottom plate l' of the calandria, constituting the floor of 55 the heating vapor conduit, it will be recalled is preferably a flat plate, sloping gently from the end of the conduit having the vapor inlet d toward and to the end of the conduit along which are arranged the 60 series of draining pipes h' for the condensate.
- In the operation of the heating system just described, the steam or other heating vapor enters at the inlet d at a high velocity, 65 a customary velocity being about 4000 feet
- per minute, and rushes along the straight-away and uni-directional conduit or chamber, parts of the vapor current impinging on and surrounding immediately the pipes m and parts of the current rushing along 70 the passages o and first impinging on and surrounding pipes relatively remotely located from the inlet d . Owing to the lower temperature of the pipes m , the heating vapors are condensed all along and throughout the chamber and fall or flow to the floor thereof, and the condensate runs rapidly to the draining outlets h' by reason both of the slope of the floor and the onrush of the 75 vapor.
- The incondensable gases do not, as is often stated, separate into gases which are either heavier or lighter than the incoming vapors, the lighter gas to conveniently float to the top tube sheet of a calandria where 80 it would be an easy matter to draw it off and get rid of it the other gas to fall to the lower tube sheet to be similarly drawn off.
- It has been found in practice that the great velocity of the vapor flow or current 85 in the interior of a calandria keeps the gases completely mixed so that any drawing off of the said gases as above described and based on their difference in specific gravity is a fallacy and cannot be obtained. Therefore 90 the importance of my invention is realized when it is stated that perforations z are made at regular intervals in the outlet tubes y throughout their entire length. The perforations in the gas outlet tubes as above 95 described make that portion of the calandria where the volumes of incondensable gases accumulate an area of multitudinous openings distributed both vertically and horizontally at spaced intervals throughout the entire rear end of the heating vapor chamber or conduit, these openings at all levels drawing directly in the mixed incondensable 100 gases which have been driven forward by the heating vapor current.
- 105 Referring to the means for supplying and conducting away the liquid undergoing concentration, and in connection therewith certain parts relating to the internal circulation thereof, the calandria in a cell is usually 110 in multiplicate of the parts already described, that is there are one or more downtakes n provided with a heating vapor chamber or conduit on each side thereof. In Figs. 1, 3 and 4 a central downtake n is shown with 115 a heating vapor chamber on each side thereof, and in Fig. 5 two down takes n are shown with a heating vapor chamber therebetween and one on the outside of each downtake.
- The inlet into the cell for the liquid to be 120 concentrated, as embodied, comprises a pipe or pipes x extending horizontally beneath the calandria, and provided on the upper side thereof, and elsewhere as desired, with 125 a plurality of spaced exit orifices x' for dis-

charging the fluid beneath the tubes m . It will be seen from the drawing that the heating vapor inlet d is at one end of the calandria and that the fluid supply pipe x enters at the other end of the calandria and extends along underneath the heating or steam chamber. The heating vapor and the fluid supplied to be heated flow in opposite directions, that is, they establish a counter current flow, which is very efficacious and rapid in the interchange of heat.

The exit means for the concentrated fluid comprises, as embodied, a pipe v extending horizontally within and near the bottom of the cell and preferably in the same direction with the pipe x . The pipe v is provided with a plurality of spaced apart exit openings v' for conducting away the concentrated liquid. This exit pipe v is located preferably beneath the downtake n , and in Figs. 1, 3 and 4, a pipe v is so shown with a supply pipe x on each side thereof under each cluster or set of the tubes m of the corresponding heating vapor conduit or chamber.

In accordance with one feature of the invention, a deflecting plate t is arranged over and along the exit pipe v and being preferably a little longer than the downtake n . The plate v is preferably formed with a longitudinal top central edge s , the sides of the plate curving outwardly and downwardly from this edge, the downcoming liquid from the downtake n being thereby deflected equally to either side and beneath the two adjacent sets of calandria pipes m . Openings u are provided through the deflecting plate t to permit a part of the downcoming liquid to pass through and into the exit pipe v , and longitudinally disposed spaces w are provided along or beneath the bottom edges of the deflecting plate t , likewise affording passages for the liquid to the pipe v , especially in the event of the openings u through plate t becoming clogged. Thus there is insured an outlet to the exit pipe v at practically no expenditure or waste of energy of the circulating liquids.

The exit pipe or pipes v of one cell or effect are connected by a pipe v' to the supply pipes x of the next succeeding cell to conduct the partially concentrated liquid thereinto to subject it to the next stage in the process of concentration, in a well-known manner. A regulating valve v^2 is preferably provided to control the flow of the liquid between the successive cells or effects.

The circulation in the cell, starting by way of example at a point midway in the tubes m , is upward, due to the heating of the tubes by the steam or other heating vapor. On emerging from the tops of the tubes m the hot but already cooling and denser liquid flows across toward the top of the downtake n , the flow of the liquid being parallel

or non-converging, and therefore all back pressure and stagnant spots and unequal circulation are avoided. As the flowing liquid becomes denser by the release of the vapor at the surface and by cooling, it descends through the downtake n , and is deflected toward either side and directed onwardly beneath the tubes m of the calandria, and by reason of the upward flow through the tubes, the liquid rises thereinto and so passes again through the circulation cycle just described. The flow from one effect to another through the pipes v for the next succeeding step in the concentration has already been described.

The pipe manifold carrying the hot liquids entering the cells I have located at the most logical position, for since the liquids run from cell to cell and the first cell is at a higher temperature than the second, the second higher than the third, etc., it follows that the liquid entering the next succeeding cell in series after it has been boiled in the preceding cell under a greater pressure than obtains in said succeeding cell, some of the liquid will flash into vapor and since the location of entrance pipe x is immediately below the heating tube clusters m , it follows that this vapor formed by the flashing from the liquids leaving the preceding cell will help boil the liquids in the cell where the liquid is now in circulation.

The transference of the heat at the location I have described is not the only advantage found however. Bubbles of steam and vapor created by the flashing into vapor just described, rising upwardly and being obliged to flow through the tubes will have the effect of aiding the circulation in the vessel, for in their natural course to the top of the liquid, the bubbles drive along the liquid in the tubes.

I have purposely made the inlet pipe x perforated with a number of small outlets. The advantage gained is that the incoming liquid from the preceding cell is divided and distributed into a number of jets and consequently the circulation is made more uniform than could be done otherwise.

As shown in Figs. 1, 2, 3, and 4, there are indicated two inlet pipes x for the incoming juice, one pipe v for the withdrawal of the juice and one downtake or circulating well n located over the pipe withdrawing the juice and one deflecting plate t . In apparatus of moderate size not more than about eight feet square this means will be sufficient to attain a proper distribution and circulation of the material undergoing evaporation. In apparatus of larger size I will employ three or more pipes to introduce and distribute the incoming liquid, two or more pipes to effect a uniform withdrawal of the liquid, two or more downtakes or circulating wells and two or more deflecting plates. All

these will be symmetrically arranged with respect to each other and substantially as indicated in Fig. 5.

The liquid being evaporated is hottest 5 while it is passing through the tube clusters and coldest when it is farthest away from the tubes.

Using this fact as a basis, I have accordingly located the outlet for the liquids in 10 the farthermost location from the hot tubes and at a point where relatively cold liquor only is passing.

Again when taking samples of material 15 undergoing evaporation from different parts in the same cell of an evaporator of the circular submerged tube type, it has been observed that the samples are often of different density.

Seeking the cause of this inequality, I 20 have come to the conclusion that either some parts of the calandria of the cell must receive a greater amount of steam or vapor than other parts or that the draw-off pipes are not correctly located causing the liquid in 25 certain parts of the apparatus to become stagnated or nearly so and to be very deficient in respect to circulation.

This effect is not only very detrimental to the rate of evaporation but also because it 30 results in some portion of the liquid undergoing evaporation being exposed for an undue length of time to the high temperature necessary to effect evaporation.

On the basis therefore that the proper location of the draw off pipes is very essential 35 to the proper working of an evaporator, I have accordingly provided numerous inlet connections regularly spaced on the exit manifold *v* throughout its entire length 40 across the bottom of the cell and directly below the downtake *n*, so that all of the liquid in the evaporator must pass in close proximity to some one of the exit connections.

The assurance that the liquids will be 45 drawn off regularly is obtained—and long continued presence of any portion of the material in the apparatus is avoided.

The bottom tube plate *l* is arranged with a fall in the direction of the flow of steam. 50 In my invention this is accomplished in the very simplest manner by using a plain flat tube plate *l* and assembling one end lower than the other.

The cylindrical standard effect is handicapped in the respect that it cannot adopt 55 this arrangement except with great mechanical difficulty.

Forging the lower tube sheet so that it 60 will form a truncated cone with an altitude of only several inches is generally resorted to, and since it is always desirable to have all tubes exactly the same length, the necessity of forging the upper tube sheet as well as the lower is easily understood.

The heating surface and evaporating capacity of the circular submerged tube evaporator is not easily enlarged, except possibly by lengthening the tubes which automatically increases the hydrostatic pressure on the liquids which in turn lowers the efficiency of 70 the apparatus.

In the apparatus as above described, enlargement of the cells is easily accomplished simply by adding additional banks of tubes and inserting and adding new sections of 75 exterior shell. In this manner the circulation of the liquid is not impaired in the slightest degree although two or more down-takes will be required.

In points of construction and ease and inexpensiveness of machine work, the square or rectangular shaped evaporator in plan section far excels the circular section apparatus.

In the square or rectangular evaporator 85 all joints will be 90 degrees which insures ease in machining, simplicity in patterns and makes a minimum number of patterns necessary.

The ribbing of the shell of the evaporator 90 necessary to make it withstand the atmospheric pressure has not been shown on the drawings but will of course be taken care of in the making of the evaporators.

The usual mountings required for every 95 evaporator will be adopted for use on the above apparatus disclosed.

An efficient save-all will be built in the domes of each cell so as to prevent entrainment of the liquid being evaporated. This 100 save-all is not shown on the accompanying drawings nor recorded in the claims at the end of this specification.

Having thus described my invention and not wishing to limit myself to the exact 105 specific construction therein disclosed, and knowing that many modifications of my invention can be made and at the same time be within its scope, I therefore claim:

1. An evaporator including in combination a substantially horizontal straight-away chamber confining and directing the flow of the inrush vapors in a single right-line direction, vertical fluid conducting tubes passing through said chambers, a common down-take passage extending along said chamber substantially for its entire length and dividing it into two parts, and receiving the flow from both sets of tubes, a supply pipe extending along beneath the 110 tubes in one chamber, a supply pipe extending along beneath the tubes in the other chamber, and a common exit pipe extending along beneath the downtake.

2. An evaporator including in combination a substantially horizontal straight-away chamber confining and directing the flow of the inrush vapors in a single 125

right-line direction, vertical fluid conducting tubes passing through said chambers, a common down-take passage extending along said chamber substantially for its entire length and dividing it into two parts and receiving the flow from both sets of tubes, a supply pipe extending along beneath the tubes in one chamber, a supply pipe extending along beneath the tubes in the other chamber, and a common exit pipe extending along beneath the downtake, a horizontally arranged deflector interposed between the downtake and exit pipe, and openings past the deflector for admitting fluid to the exit pipe.

3. An evaporator including in combination a substantially horizontal straight-away chamber confining and directing the flow of the inrushing vapors in a single right-line direction, vertical fluid conducting tubes passing through said chambers, a common down-take passage extending

along said chamber substantially for its entire length and dividing it into two parts and receiving the flow from both sets of tubes, and means within and at the rear and bottom of said straight-away chambers for carrying away the condensates and means within and at the rear and upper portions of said chambers for carrying away the non-condensable vapors.

4. An evaporator including in combination a calandria, comprising a straight-away conduit along which the heating vapor travels, a plurality of fluid conducting pipes passing therethrough, and a fluid supply pipe running along beneath the calandria, the conduit and fluid supply pipe being connected to have a counter current flow.
